[57] CLAIM

The ornamental design for a communication equipment
cover as shown and described.

DESCRIPTION

FIG. 1 is a top front perspective view of a communica-
tion equipment cover in accordance with our new de-
sign;

FIG. 2 is a top plan view thereof;

FIG. 3 is a side elevation view thereof, the opposite side
being essentially a mirror image of the side shown;

FIG. 4 is a front elevation view thereof;

FIG. 5 is a bottom plan view thereof.

The broken lines representing equipment housing are
shown for illustrative purposes only.

FIG. 2

FIG. 3

FIG. 4

FIG. 5
